PARAMOUNT KNITTING CO., OF CHICAGO, ILLINOIS, A CORPORATION OF ILLINOIS.

KNITTING-MACHINE NEEDLE.

1,096,945.

Specification of Letters Patent.

Patented May 19, 1914.

Application filed December 28, 1909. Serial No. 535,323.

To all whom it may concern:

Be it known that we, FRANK POPE and EDISON E. RANDALL, citizens of the United States, and residents of Kankakee, county of 5 Kankakee, State of Illinois, have invented an Improvement in Knitting-Machine Needles, of which the following description, in connection with the accompanying drawing, is a specification, like characters on the 10 drawing representing like parts.

This invention relates to a knitting machine and particularly to the needle and the means for operating it.

This invention is designed to take the 15 place of that type of needle known as the "latch" needle and the machine in which it is used.

The latch needle with its pivoted latch is 20 open to serious defects inherent in its construction and operation owing to the minute character of the pivotal joint, the continuous swinging of the latch on the pivot, the non-positive action of the latch, the extent of movement of the needle required to form 25 the stitch, and for other reasons familiar to those skilled in this art.

The present invention presents a machine and a needle in which the needle is made up 30 of two separate independently movable members, one formed to present the usual hook and which is herein termed the "hook member," and the other performing the functions 35 of the usual latch and which is herein termed the "latch member." These members are 40 separately and positively actuated to cause the coöperation of the latch with the hook to cover and uncover the hook at the proper time. The movements being positive and the construction being exceedingly simple 45 and strong in principle remedies substantially all the defects existing in and the objections to the pivoted latch needle. Furthermore the invention is readily adapted to existing knitting machines, requiring but slight alteration of such machines.

The nature of the invention will appear 50 more fully from the accompanying description and drawings and will be particularly defined in the appended claims.

The drawings represent a preferred form 55 of needle embodying the invention, the needle being shown in connection with so much of an ordinary plain circular knitting machine as is necessary for an understanding of its operation.

In the drawings, Figure 1 is a view chiefly in cross section of the upper portion of the needle and cam cylinders of an ordinary type of plain circular knitting machine showing a needle of the preferred form of 60 this invention in position; Fig. 2 is a side view, and Fig. 3 a rear elevation of the latch member enlarged of the preferred form of needle embodying the invention; Fig. 4 is a view in cross section of the needle cylinder 65 showing a needle such as illustrated in Fig. 1 in position with the hook member of the needle partially in cross section; Fig. 5 is a view similar to Fig. 4 showing the needle in depressed position; Fig. 6 is a view chiefly 70 in cross section of the upper end of the hook member of the preferred form of needle shown in Fig. 1.

It is unnecessary herein to describe any particular form of knitting machine because the needle of this invention is adapted 75 to replace the ordinary pivoted latch needle in any form of machine where the latter is used and very little modification of any such machine will be found necessary to adapt the 80 needle of this invention thereto. For convenience there is illustrated in Fig. 1 a portion of the cam and needle cylinders of an ordinary type of plain circular knitting machine. In this figure the needle cylinder is 85 shown at 1 and the cam cylinder at 2.

A needle embodying the present invention comprises physically-separated or disconnected coöperating hook and latch members 90 relatively movable to cause the coöperation of the latch and hook.

Referring to the drawing, the hook member of the needle 3 is of practically the same form as the corresponding member of the ordinary pivoted latch needle comprising 95 the hooked end 4 and a shank and butt 5 which vary in length, shape and proportion according to the particular style of needle in a well known manner. The hook member 3 is slotted at 6 near its forward end at about 100 the position of the usual slot for the pivoted latch, and this slot is preferably made in the form of a saw kerf entering the hook member from the front so that the end walls of the slot converge rearwardly and present at 105 the rear surface of the hook member shoulders 7 and 8. The hook member is mounted to slide longitudinally in a groove 9 formed in the usual manner in the exterior surface of the needle cylinder, and it is given its 110

longitudinal movement in the usual manner as by engagement of its butt 5 with a cam 10 on the face of the cam cylinder 2. In this preferred form of the invention, the latch member is preferably made of sheet metal 5 and of a thickness such as will allow it to move readily within the slot 6 of the hook member. This latch member is shown in Figs. 2 and 3 and comprises a head 11 and a tail 12. A longitudinal auxiliary groove 13 to receive the latch member is formed in the needle cylinder directly and centrally back of or beneath the needle groove 9. The head of the latch member is provided with upper 14 and lower or forward and rear cam surfaces 15, respectively, and with upper and lower or forward and rear shoulders 16 and 17. The head of the latch member projects 20 into the slot 6 of the hook member and the cam surface 14 and the shoulder 16 are adapted to coöperate with the shoulder 7 of the hook member, while the cam surface 15 and shoulder 17 are adapted to coöperate 25 with the shoulder 8 of the hook member. The tail 12 of the latch member slides within the groove 13 and is in frictional engagement therewith so that it will not move unless positively operated. To secure this 30 frictional engagement, the tail is preferably bent as indicated at 18. The cam surfaces are so shaped and the distance between the shoulders 16 and 17 as compared with the distance between the shoulders 7 and 8 is 35 such that the movement of the hook member longitudinally under the control of its operating cam results in the various movements of the members of the needle. Thus starting with the needle in the position shown in 40 Figs. 1 and 4, the yarn is fed beneath the hook 4 of the hook member; the hook member is retracted or moved downwardly by the cam engaging the butt 5 until the shoulder 7 engages the cam surface 14; the shoulder 7 acting on the cam surface 14 moves 45 the latch member laterally or transversely of the hook member within the slot so as to project the latch end 19 beneath the hook 4 just free of the hook and covering the hook 50 or in such position that the thread will be shunted over the point of the hook; as the hook member continues its retracted or downward movement it carries with it the latch, the parts then being as indicated in 55 Fig. 5, until the limit of movement is reached; when the hook member rises or moves forward it moves by itself independently of the latch member for a short distance and then the shoulder 8 engages the 60 cam surface 15 moving the latch laterally or transversely of the hook member backward; the hook member continuing its forward or upward movement carries the latch member with it to a position where it will 65 be ready again to be projected at the proper

time upon the retraction of the hook member.

It will thus be seen that the latch and hook members have relative longitudinal and transverse bodily movement and that the operation of the members of the needle is positive and that the longitudinal movement of the needle necessary to take and cast off the loops is much less than in the case of the pivoted latch needle, thus enabling a 70 needle-operating cam of flatter angle to be used and consequently less wear and strain upon the butts of the needle. The action of the members of the needle is positive, the shoulders on the hook member coöperating 75 with the cam surfaces and shoulders on the latch member to move the latter positively into and out of coöperative position.

By the term latch member is to be understood any device coöperating with the hook 80 of the hook member and covering and uncovering the point of the hook to secure the passage of a loop of thread past the point of the hook or the point of the hook through 85 the loop without catching.

Having fully described our invention, what we claim as new and desire to secure by Letters Patent is:

1. A knitting machine needle comprising a longitudinally slotted hook member, a latch 95 member provided with a head entering said slot and independently movable longitudinally and transversely of said hook member, and means on said members for causing longitudinal and transverse movements of the 100 latch member to cover and uncover the hook upon the reciprocation of the hook member.

2. A knitting machine needle comprising a longitudinally slotted hook member and a latch member having relative longitudinal 105 and transverse bodily movement through the slotted portion of said hook member into and out of coöperative relation therewith.

3. A knitting machine needle comprising a longitudinally slotted hook member and a 110 latch member having relative longitudinal and transverse bodily movement through the slotted portion of said hook member into and out of coöperative relation therewith, and means governed by the operation of the 115 hook member to effect the movement of the latch member.

4. A knitting machine needle comprising a longitudinally slotted hook member and a latch member having relative longitudinal 120 and transverse bodily movement through the slotted portion of said hook member into and out of coöperative relation therewith, the said members engaging upon each reciprocation to effect the movement of the 125 one from the other.

5. In a knitting machine a knitting machine needle comprising a hook member slotted longitudinally, a latch member projecting into said slot and provided with cam 130

surfaces coöperating respectively with the walls of said slot whereby upon the forward movement of the hook member the latch member will be drawn into the slot and upon 5 the retraction of the hook member will be projected through the slot to cover the hook, and means for effecting the movement of the hook member.

6. In a knitting machine a knitting machine needle comprising a hook member slotted longitudinally, a latch member projecting into said slot and provided with oppositely disposed cam surfaces and shoulders coöperating respectively with the walls of 10 said slot whereby upon the forward movement of the hook member one cam surface will act to withdraw the latch member into the slot, one shoulder will act to cause the forward movement of the latch member by 15 the hook member, and upon the retraction of the hook member the other cam surface will act to cause the latch member to be projected from the slot to cover the hook and the other shoulder will act to cause the latch 20 member to be retracted by the hook member without contacting with the hook, and means for effecting the movement of the hook member.

7. In a knitting machine a needle bed presenting a longitudinal slot in its face to receive and guide a needle member and an auxiliary longitudinal slot beneath said main slot to receive and guide a second needle member, a needle comprising a hook member and a latch member longitudinally movable bodily, the said needle members mounted to move in said slots, one needle member frictionally engaging its slot to secure a retardation of movement, and means 30 for effecting the coöperating movement of said member from the other member upon the movement of the other member in its slot.

8. In a knitting machine a needle comprising a hook member and a separate latch member having relative longitudinal bodily movement into and out of coöperative relation, a needle bed provided with superimposed slots of different widths one for each 40 of said members, means independent of one member for creating retarding friction between the other of said members and the walls of its slot, and means for giving posi-

tive longitudinal movement to the first of said members to bring said members into co- 55 operative relation.

9. In a knitting machine a needle comprising a longitudinally slotted hook member, a separate latch member movable longitudinally and laterally in said slot to cover 60 and uncover the hook, a needle bed provided with superimposed slots, one for each of said members, means independent of the hook member for creating retarding friction between the latch member and the walls of 65 its slot, means for giving positive lateral movement to the hook member, and means governed by the movement of the hook member to effect the movement of the latch member therefrom.

10. In a knitting machine, a knitting machine needle comprising a hook member slotted longitudinally, a latch member projecting into said slot and provided with a cam surface coöperating with a wall of said 70 slot whereby upon the retraction of the hook member the latch member will be projected through the slot to cover the hook, and means for effecting a longitudinal movement of the hook member.

11. In a knitting machine, a needle comprising a longitudinally slotted hook member, a latch member having relative bodily movement through the slotted portion of said hook member into and out of coöperative relation therewith, and means independent of the hook member and located at the rear of the hook member opposite the hook face for creating friction on the latch member.

12. In a knitting machine a needle comprising a hook member and a separate latch member having relative longitudinal bodily movement into and out of coöperative relation, and a needle bed provided with superimposed slots of different widths one for each of said members.

In testimony whereof, we have signed our names to this specification, in the presence of two subscribing witnesses.
